CURRENT COLLECTOR

Edwin E. Arnold, Pittsburgh, Pa., assignor to Westinghouse Electric & Manufacturing Company, East Pittsburgh, Pa., a corporation of Pennsylvania

Application June 28, 1940, Serial No. 342,908

10 Claims. (Cl. 191—59.1)

My invention relates, generally, to current collectors, and it has reference, in particular, to current collectors of the slider shoe type for collecting current from a trolley conductor for electrically operated vehicles.

Generally stated, it is an object of my invention to provide a current collector of simple construction, and which is inexpensive to manufacture and efficient and durable in operation.

More specifically, it is an object of my invention to provide for pivotally supporting a slider shoe of a current collector on a support member for universal movement about a substantial point contact utilizing retaining means for normally securing the slider shoe in operating relation with the support member, and providing auxiliary retaining means for preventing accidental separation of the slider shoe and the support member.

Another object of my invention is to provide for maintaining a predetermined minimum contact pressure at a contact point between a slider shoe and a support, and utilizing auxiliary retaining means for preventing accidental removal of the slider shoe from the support.

A further object of my invention is to provide for resiliently retaining a slider shoe and a support member in a predetermined operating relation and protecting the retaining means by utilizing auxiliary normally ineffective retaining means for limiting the degree of separation of the slider shoe and the support member.

Still another object of the invention is to provide for detachably securing a depending skirt and a slider shoe in fixed relation and retaining them in operating relation with a support member by resilient retaining means.

Other objects will, in part, be obvious and will, in part, be indicated hereinafter.

In practicing my invention, a slider shoe for a current collector on an electrically operated vehicle may be pivotally supported by a support member so as to oscillate about a substantial point contact therebetween, through which the current may be conducted from the slider shoe. A depending skirt may be attached to the slider shoe by adjustable clamp members positioned on each side of the shoe so as to substantially enclose the point of contact between the slider shoe and the support member. Spring members may be operatively connected to the clamp members and the support member within the depending skirt for maintaining the slider shoe and the support member in predetermined operating relation. A dependent portion of the skirt may be normally positioned in spaced relation to means on the

support member, and disposed to cooperate therewith under any unusual conditions to prevent accidental separation of the slider shoe and the support member and protect the spring members.

5 For a more complete understanding of the nature and scope of my invention, reference may be had to the following detailed description and the accompanying drawings in which:

Figure 1 is a side elevational view of a current collector embodying the principal features of my invention;

Fig. 2 is a plan view of the current collector of Fig. 1;

Fig. 3 is a sectional view along the line III—III of Fig. 1;

Fig. 4 is a side elevational view of the support member;

Fig. 5 is a cross-section view of the slider shoe;

Fig. 6 is a longitudinal sectional view of the slider shoe;

Fig. 7 is a plan view of the skirt member;

Fig. 8 is a side view in elevation of the skirt member;

Fig. 9 is an end elevational view of the skirt member;

Fig. 10 is a plan view of a clamp member;

Fig. 11 is a side elevational view of the clamp member;

Fig. 12 is a plan view of a current collector embodying a modification of the invention;

Fig. 13 is a side elevational view partly in section, of the current collector of Fig. 12; and

Fig. 14 is an end elevational view, partly in section, of the current collector of Fig. 12.

35 Referring to Figs. 1, 2 and 3 of the drawings, the reference numeral 10 may denote generally a current collector comprising, for example, a grooved slider shoe 12 for engaging a trolley conductor (not shown), a body member 14 for attachment to a trolley pole or the like, and a support member 16 for pivotally supporting the slider shoe on the body member.

The slider shoe 12 may be provided with a depending housing or skirt member 18 which substantially encloses the support member. For the purpose of securing the slider shoe and the skirt member together, suitable means such as the clamp members 20 may be provided, which may be positioned on each side of the slider shoe. By 45 utilizing bolts 22 and nuts 24 for adjustably securing the clamp members to the skirt member 18, the slider shoe may be readily secured to the skirt member or detached therefrom for effecting renewals.

In order to secure the slider shoe 12 and the

skirt member 18 in predetermined operating relation to the support member 16 suitable retaining means may be provided. For example, a ball-bearing retaining ring 26 of the thrust type may be rotatably mounted on the support member 16, and resilient retaining members such as the springs 28 may be operatively connected between the ring and the slider shoe. For example, the lower ends of the springs 28 may be hooked through openings 30 on opposite sides of the retaining ring 26, while the upper ends may be secured to means such as the depending ears 32 on the lower sides of the clamp members 20 which engage the slider shoe.

The slider shoe 12 and the skirt member 18 may thus be secured on the support member 16 for oscillation in a plurality of planes about the point of contact therebetween. The retaining springs 28 are effective to maintain a predetermined minimum contact pressure at the point of contact between the slider shoe and the support member to insure the proper current conducting characteristics for efficient operation of the current collector.

The body member 14 may be of any suitable construction being, for example, formed from sheet metal and having a substantially vertical socket 34 for receiving the support member 16, and an angularly related socket portion 36 for receiving a trolley pole, or trolley pole extension 38. Means, such as the bolts 40, may be provided for firmly securing the trolley pole or trolley pole extension in the socket 36.

Referring to Fig. 4 of the drawings, it may be seen that the support member 16 may comprise a substantially cylindrical central body portion 42 having a threaded extension 44 of reduced section at the lower end for receiving a nut, by means of which the support member may be secured in the socket 34 of the body member. Suitable means may be provided for preventing rotation of the support member 16 in the socket 34, such as, for example, the flattened side portions 46 adjacent the threaded extension 44, which may cooperate with a similarly flattened side portion of the opening in the bottom of the socket 34. An enlarged end portion 48 may be provided adjacent the upper end of the support member so as to define a peripheral shoulder 50, which may be used for a purpose which will be hereinafter explained.

In order to pivotally support the slider shoe 12, the support member 16 may be provided with a substantially pointed contact member 52 at the upper end, which is preferably of a relatively hard material having a relatively low electrical resistance. Beryllium copper alloys may, for example, be used successfully for this purpose. The contact member 52 may be secured to the support member in any suitable manner, being for example, exteriorly threaded for engaging corresponding threads on the interior of a central opening 54 in the upper end of the support stem.

By referring to Figs. 5 and 6 it may be seen that the slider shoe 12 may be generally of any suitable construction comprising, for example, an elongated body member 56 of a non-ferrous metal, such as aluminum, bronze, or the like, and having a longitudinal groove 58 on the upper side with upstanding lips 60 for receiving a trolley conductor (not shown). In order to secure the desired wear and current conducting characteristics, the body member 56 may be provided with a wear and current conducting insert 62 to pro-

vide a bearing surface on at least the bottom of the groove 58 for engaging the trolley conductor. The insert 62 may be of any suitable nature comprising, for example, either a carbonaceous compound, or the like, or a relatively hard metallic insert, depending upon the particular wear or current conducting characteristics desired.

With a view to pivotally supporting the slider shoe 12 on the contact member 52, suitable means may be provided for receiving the contact member 52, such as, for example, the substantially conical recess 66 on the lower side of the slider shoe. In order to provide substantially point contact so as to secure the proper current conducting characteristics and permit the slider shoe to oscillate freely on the contact member 52, the sides of the conical recess 66 should subtend a relatively wide angle compared with the angle included between the sloping sides of the contact member 52. Where it is desired to form the body member 56 of the slider shoe of a relatively soft non-ferrous metal, it may be expedient to provide a hardened insert 68 of a material such as tool steel or chilled cast iron on the lower side of the slider shoe having the recess 66 formed therein, so as to provide a suitable supporting and current conducting contact with the contact member 52 of the support member 16. The wear insert 62 and the insert 68 may be positioned in the body member 56 in any suitable manner, being, for example, cast integral therewith, so that an intimate current conducting contact is secured therebetween. Suitable means may be provided for assisting in aligning the slider shoe on the skirt member, such as, for example, the projections 70 on the lower side thereof adjacent the ends. Projecting side portions 72 may be provided on each side of the body member 56 adjacent the lower side for engagement with the clamp members 20 to assist in securing the slider shoe to the skirt member 18.

Referring to Figs. 7, 8 and 9, it will be apparent that the skirt member 18 may, for example, comprise a substantially hemispherical shell 74, having a relatively flat top portion 76. An elongated opening 78 may be provided in the bottom of the shell 74 for receiving the central body portion 42 of the support member 16. The sides 80 of the opening may be substantially parallel, and spaced apart sufficiently so as to permit movement of the skirt relative to the support member. A central opening 82 may be provided in the top 76 of the skirt member for receiving the insert 68 on the lower side of the slider shoe, so that the contact member 52 may be positioned in the recess 66 thereof. Suitable openings 84 may also be provided in the top 76 for receiving the projections 70 on the lower side of the slider shoe 12, for the purpose of properly aligning the slider shoe on the skirt member. With a view to securing the slider shoe 12 and the skirt member 18 in fixed relation, means such as the cored-out openings 86, may be provided on each side of the shell 74 of the skirt member for receiving the nuts 24. Suitable bolt holes 88 may be provided in the top of the skirt member for the bolts 22 by means of which the clamp members may be detachably secured to the skirt member. Means such as the openings 90 may be provided in the top of the skirt member at each side for receiving the depending ears 32 of the clamp members. With a view to assisting in securing the slider shoe and the skirt member, shoulder portions 92 may be provided at the outer edges of the top 76 to function as fulcrums for the clamp members 20.

Referring to Figs. 10 and 11, it will be obvious that the clamp members may, for example, comprise substantially flat plate portions 94 having the ends shaped to conform with the contour of the skirt member. Means such as the depending ears 32 may be positioned on the lower sides, having openings 96 therein for receiving the ends of the retaining springs 28. Suitable openings 98 may be provided in the plate portions adjacent the ends for receiving the bolts 22 by means of which they may be attached to the skirt member. Openings 99 may also be provided in the plate portions 94 so that a suitable tool may be inserted therein to tilt the clamp members on edge to facilitate placing the slider shoe 12 in position or removing it therefrom.

In assembling the current collector, the retaining ring 26 may be slipped onto the central body portion 42 of the support stem 16, so that it fits up against the peripheral shoulder 50. The lower end 44 of the support stem 16 may then be inserted through the top opening 82 and the opening 78 of the bottom of the skirt member 18, and positioned in the socket 34 of the body member 14 of the current collector, where it may be rigidly secured by means of the nut 100. The lower ends of the retaining springs 28 may then be inserted in the openings 30 of the retaining ring 26, and the upper ends thereof may be hooked through the openings 96 in the depending ears 32 of the clamp members 20 by drawing them up through the openings 90 provided for that purpose on each side of the top of the skirt member. The slider shoe 12 may then be positioned with the contact member 52 in the recess 66, and secured in fixed relation to the skirt member 18 by inserting a suitable tool in one of the openings 99 of the clamp members and tilting it on edge so that the side portions 72 of the slider shoe may be positioned under the edges of the clamp members 20, positioning the bolts 22 through the openings 98 in the clamp members and the corresponding openings 86 in the top portion of the skirt member, and tightening the nuts 24.

The slider shoe 12 is then free to oscillate on the contact member 52 of the support member 16, being limited only by the sides 80 of the opening 78 in the bottom of the skirt member, which prevent oscillation of the slider shoe about an axis parallel to the longitudinal axis of the slider shoe, or the groove 58. The retaining springs 28 normally provide a predetermined minimum contact pressure between the contact member 52 and the insert 68 in the bottom of the slider shoe, so as to normally prevent any separation of these members and provide a relatively good conducting path for collecting current from the slider shoe.

It will be observed that the sides 80 of the opening 78 in the bottom of the skirt member 18 normally limit only the degree of oscillation of the slider shoe 12 and the skirt member 18 on the contact member 52, and do not otherwise engage or interfere with the support member. However, should there be a tendency for the slider shoe 12 and the skirt member 18 to be separated from the support member 16 under any unusual operating conditions, such as when the current collector is derailed and becomes entangled with a guy wire or the like, the sides 80 of the opening 78 engage the lower side of the retaining ring 26, which is secured against upward movement on the support member 16 by the peripheral shoulder 50. In this manner, an auxiliary retaining means is provided for preventing accidental removal of the slider shoe from the contact member, and protecting

the retaining springs 28 from undue strains, so as to preserve their normal operating characteristics.

Referring to Figs. 12, 13 and 14 of the drawings, which illustrate a modification of the invention, the reference numeral 110 may denote generally a current collector comprising a slider shoe 112 pivotally supported on the contact member 114 of a support member 116, which is positioned in a body member 118 having a socket portion 120 for receiving a trolley pole or trolley pole extension 122.

In this modification of the invention, the slider shoe 112 may be provided with a substantially conical recess 124 on the lower side for receiving the contact member 114, and an elongated groove 126, in the upper side for receiving a trolley wire. Flanged side portions 128 may be provided having opening therethrough for receiving means, such as the bolts 130, for attaching a depending skirt member 132 thereto. Suitable means, such as the rivets 134, may be positioned in openings 136 in the flanged side portions 128 for securing the upper ends of retaining springs 138. The lower ends of the retaining springs 138 may be secured by means such as the extending ears 140 of a retaining or thrust ring 142, which may be rotatably mounted on the support member 116 and positioned against a peripheral shoulder 144 thereof.

For the purpose of preventing accidental removal of the slider shoe 112 and the skirt member 132 from the support member 116, during operation, auxiliary retaining means may be provided. For example, a support member 116 may be provided with an enlarged head portion 146 at the upper end, forming a peripheral shoulder 148. The depending sides 150 of the skirt member 132 may be provided with inwardly projecting portions 152 at the lower end thereof, having sufficient clearance therebetween to normally freely permit motion of the skirt member 132 relative to the support member in the vertical plane passing through the longitudinal axis of the slider shoe, but adapted to interfere with the peripheral shoulder 148 if there should be any tendency of the slider shoe to separate from the contact member during operation. Thus, should any excessive force be applied to the slider shoe and skirt member, tending to remove them from the support member, the inwardly projecting portions 152 will engage the peripheral shoulder 148 to prevent the removal. At the same time, this cooperation of the inwardly projecting edge portions 152 and the peripheral shoulder 148 protects the retaining springs 138 from excessive loading, thus assisting in retaining the desired operating characteristics of the current collector. The enlarged head portion 146 may be slightly elongated if desired, so that the projecting front and rear portions engage the depending sides 150 of the skirt member interfere therewith after a predetermined degree of rotation of the slider shoe and skirt member about a vertical axis. Limited rotation of the slider shoe is thus provided for.

From the above description and the accompanying drawings, it will be apparent that I have, by my invention, provided a current collector of simple construction, which may be readily manufactured, and which is efficient and durable in operation. In a current collector embodying the features of my invention, the slider shoe may be readily removed therefrom for renewal or inspection purposes with a minimum of effort. Such a current collector has very desir-

able operating characteristics, since the slider shoe may freely oscillate about a point of contact between the slider shoe and the support member. Because of the relatively high contact pressure which may be maintained between the contact member and the slider shoe, the current carrying characteristics thereof remain substantially unaffected over long periods of use and the undesirable heating normally encountered in current collectors is materially reduced. The auxiliary retaining means effectively prevents the accidental removal of the slider shoe from the contact member, and also protects the retaining springs so as to assist in preserving the desired operating characteristics.

Since certain changes may be made in the above description, and different embodiments of the invention may be made without departing from the spirit thereof, it is intended that all the matter contained in the above description or shown in the accompanying drawings, shall be considered as illustrative, and not in a limiting sense.

I claim as my invention:

1. A current collector comprising, a support, 25 a slider shoe loosely positioned on the support in pivotal relation therewith, resilient retaining means for normally maintaining the slider shoe on the support, and normally inoperative auxiliary retaining means cooperative with the support only after predetermined deformation of the resilient retaining means to limit the degree of separation of the slider shoe and the support.

2. A current collector comprising, a slider shoe, 35 support means positioned beneath the slider shoe for supporting the slider shoe including relatively movable surfaces having a substantially point contact therebetween to provide for oscillation of the slider shoe in a plurality of planes about said substantially point contact, resilient retaining means connecting the slider shoe and the support means normally effective to secure the slider shoe of the support means, and a skirt member dependent from the slider shoe cooperative with the supporting means only after predetermined deformation of the resilient retaining means to prevent accidental removal of the slider shoe therefrom.

3. In a current collector, in combination, a support member, a slider shoe supported on the support member for substantially universal movement having a groove on the upper side for engaging a trolley conductor and a hardened insert on the lower side in substantially point contact relation with the support member, retaining means for normally securing the slider shoe and the support member in predetermined relation, and normally inoperative auxiliary retaining means cooperative with the support member under abnormal conditions to prevent accidental removal of the slider shoe from the support member.

4. In combination, a slider shoe, a support positioned beneath the slide shoe for pivotally supporting the slider shoe in substantially point contact relation, a housing positioned beneath the slider shoe, means for detachably securing the slider shoe and the housing in fixed relation, retaining means positioned within the housing normally effective to secure the slider shoe and the housing in operating relation with the support, and normally inoperative auxiliary retaining means on the housing cooperative with the support upon predetermined deformation of the 75

retaining means for preventing accidental separation of the slider shoe and support.

5. A current collector comprising a substantially vertical support, a slider shoe loosely positioned on and having substantially point contact with the support, a skirt member positioned about the support, means secured to the upper side of the skirt member for detachably securing the slider shoe and the skirt member in fixed relation, resilient retaining means normally cooperative with the said means to maintain the slider shoe on the support, and normally inoperative retaining means on the skirt member cooperative with the support upon a predetermined separation of the shoe and support to prevent greater than said predetermined separation of the slider shoe and the support.

6. In a current collector, in combination, a support, a slider shoe substantially loosely positioned on the support in pivotal relation thereto, a housing dependent from the slider shoe, clamp members positioned on the upper portion of the housing on each side of the slider shoe for detachably securing the slider shoe and housing in fixed relation, retaining means including resilient means to normally secure the slider shoe on the support in operating relation, and normally inoperative means on the housing cooperative with the support upon a predetermined deformation of the resilient retaining means to prevent more than said predetermined separation of the slider shoe and support.

7. A current collector comprising, a slider shoe body having a groove on the upper side with a wear insert providing a conductor engaging surface in the groove and a hardened insert on the lower side cast integral therewith, a support member having a contact portion positioned beneath the slider shoe engaging the insert in the lower side of the slider shoe in substantially point contact relation for pivotally supporting the slider shoe about the point contact, therebetween, a housing having side portions dependent from the shoe, clamp means detachably securing the housing and slider shoe, and resilient retaining means positioned within the housing operatively connected between the clamp means and the support member for securing the slider shoe and the support member in operating relation and maintaining a predetermined contact pressure therebetween.

8. In a current collector, in combination, a slider shoe, a substantially vertical support positioned beneath the slider shoe having a removable pointed contact member for pivotally supporting the slider shoe on the point thereof and conducting current therefrom, a housing positioned about the support beneath the shoe, means for detachably securing the slider shoe and the housing in fixed relation, a pair of springs positioned within the housing cooperative with said means normally operable to maintain the slider shoe and pointed contact member in a predetermined operating relation, and means on the housing normally spaced from the support operable to engage the support to prevent accidental separation of the slider shoe and contact member upon predetermined deformation of the springs.

9. A current collector comprising, a support having a pointed contact member at the upper end, a housing having an elongated opening in the lower portion for receiving the support and allowing relative movement therebetween and an opening in the top, a slider shoe positioned on

the housing having a portion over the opening in the top for engaging the point of the pointed contact member, means secured to the top of the housing to engage the slider shoe for detachably securing it to the housing, and a pair of springs operatively connected to the said means and to the support to maintain the slider shoe and the support in predetermined operating relation.

10. A current collector comprising, a slider shoe having a groove in the upper side for engaging a trolley conductor, a substantially vertical support member having a pointed contact member positioned beneath the slider shoe for pivotally supporting the slider shoe for substantially universal movement about the point thereof and an

enlarged shoulder portion adjacent the upper end, a retaining ring positioned on the support member adjacent the shoulder portion, resilient retaining means on opposite sides of the slider shoe operatively connected to the slider shoe and the retaining ring normally operable to retain the shoe on the support member, and a housing secured to the slider shoe having an elongated central opening therein for receiving the support member with inwardly projecting side portions normally spaced from the shoulder portions of the support member operable to engage the shoulder portions upon predetermined separation of the shoe and support member to provide auxiliary retaining means.

EDWIN E. ARNOLD.
